UNITED STATES PATENT OFFICE.

KAREN M. PHILLIPS, OF NEW YORK, N. Y.

ASTROLOGICAL CLOCK.

1,171,458.

Specification of Letters Patent. Patented Feb. 15, 1916.

Application filed July 3, 1914. Serial No. 848,844.

To all whom it may concern:

Be it known that I, KAREN M. PHILLIPS, of New York, in the county of New York, and in the State of New York, have invented a certain new and useful Improvement in Astrological Clocks, and do hereby declare that the following is a full, clear, and exact description thereof.

My invention relates particularly to 10 clocks, or clock attachments, which are adapted to readily indicate astrological conclusions according to the day of the year and the time of the day.

The object of my invention is to provide 15 an apparatus of this character by means of which a person may readily determine without calculations, the zodiacal signs corresponding to the day of the year, and at the same time, the house corresponding to the 20 particular hour of the day, thus indicating for that particular hour in the year simultaneously the characteristics and destiny to be expected for any event happening at that time coming under the zodiacal signs, the 25 symbols of the signs of the zodiac, as well as the names thereof and the stars corresponding thereto and the house, and the hours and minutes of the days.

While my invention is capable of embodiment in many different forms, for the purpose of illustration, I have shown only one form thereof in the accompanying drawings, in which,

Figures 1 and 1^a show each one half of 35 a plan view of the face of a clock made in accordance with my invention; and Fig. 2 is a side elevation partly in section of the same shown as mechanically operated by a clock mechanism.

In the drawings I have shown a stationary clock dial 1 having a removable calendar 2, which may be supported in slots or recesses 3 on its face. This stationary dial 1 is provided with a number of circular 40 sub-divisions. The innermost sub-division is a circular space 4 giving the hours of the day. Next to this there is a circular space 5 giving sub-divisions of the hours. Adjacent to this there is a circular space 6 giving the 45 minutes. Next to this there is a circular space 7 giving the hours of the day according to the divisions thereof into twenty-four hours. The next space is a circular space 8 indicating the position of the sun. Adjacent to this there is supported upon the 50 dial 1, and removably attached thereto in

any suitable way, an annular dial 8^a, having a circular space 9 indicating the house corresponding to a particular hour in the day, and next to this there is a circular space 10 indicating the destiny of persons coming under the same. Supported either above or below the dials 1 and 8^a, there is a movable dial 10^a, which is adapted to rotate the same as the hour hand of a clock, one 60 complete revolution every twenty-four hours. This rotatable dial has a plurality of radiating lines 10^b, dividing this movable dial 10^a radially into sub-divisions corresponding to the two-hour distances on the stationary dial 1, and circular sub-divisions, dividing it into circular spaces. The innermost spaces are circular spaces 11, 12 and 13 which indicate respectively the star, the 65 name and the symbol of a particular part of 70 the zodiac. Adjacent to the space 13 there are a plurality of circular spaces 14, indicating the characteristics of persons, the zodiacal sign and the interval of the year to which this part of the zodiac corresponds. 75 Beynd the circular spaces 14 there is a further circular space 15 which gives the days of the month. Upon the edge of the movable dial 10^a, there is an adjustable representation of the sun 16, which is adapted to 80 be adjusted by hand to indicate the particular day in which a person is interested, and which is adjusted manually so as to be placed opposite that particular day for convenience in reading the dials. It may, for 85 example, be placed manually opposite the several days of the month as they are reached.

While my apparatus is adapted to be operated entirely manually, it may, if desired, 90 be operated mechanically by clock mechanism, and in Fig. 2 I have shown my apparatus arranged in this manner. In this figure, there is shown a clock mechanism 17, having a central shaft 18 for operating an 100 hour hand 19. Around the shaft 18 there is a stationary sleeve 20, which supports in place the stationary dial 1, upon which is carried the annular dial 8^a. Outside of the 105 sleeve 20 there is a rotary sleeve 21, which is rotated one revolution every twenty-four hours, the same as the hour hand 19, and which supports the movable dial 10^a so as to rotate the same.

By the use of my invention, a person may 110 tell the hour of the day, and may readily determine for a particular hour on a par-

ticular day the zodiacal sign, the name thereof, the symbol thereof, the star corresponding thereto and the characteristics and destiny to be expected for any event happening in that hour of that day, merely by making the readings opposite to the representation of the sun 16. In this way the complete readings or horoscope for a particular hour of a certain day may be obtained. For example, if the horoscope of a person born on the 21st day of March, between the hours of four and six were to be determined, the adjustable sun 16 would be moved into the position shown in Fig. 1, and when the movable dial 10^a had reached the position opposite the hours from four to six the readings would be made from the various dials, thus finding that the horoscope indicated the first house, life and health, Mars and Aries, and all of the characteristics of persons located in the segment of the movable dial 10^a immediately opposite the sun as shown in Fig. 1 and comprising the days from April 19 to March 21.

While I have described my invention above in detail, I wish it to be understood that many changes may be made therein without departing from the spirit of my invention.

I claim:

1. In a registering device, a stationary dial indicating the hours of the day, a movable dial extending beyond the edge of the

stationary dial and having radial dividing lines spaced apart distances corresponding to the two-hour divisions of the stationary dial, and concentric circles intersecting the lines providing segmental annular spaces designating the different parts of the zodiac and personal characteristics corresponding to certain days in the year and a representation of the sun adjustable with regard to both the stationary and movable dials.

2. In a registering device, a stationary dial indicating the hours of the day, a removable dial thereon indicating the house and destiny corresponding to a particular hour in the day, a movable dial extending beyond the edge of the stationary dial and having radial dividing lines spaced apart distances corresponding to the two-hour divisions of the stationary dial, and concentric circles intersecting the lines providing segmental annular spaces designating the different parts of the zodiac and personal characteristics corresponding to certain days in the year and a representation of the sun adjustable with regard to both the stationary and movable dials.

In testimony that I claim the foregoing I have hereunto set my hand.

KAREN M. PHILLIPS.
